Application July 1, 1947, Serial No. 140,051

(Cl. D29—23)

To all whom it may concern:

Be it known that I, Otto A. Kuhler, a citizen of the United States, residing in Blauvelt, in the county of Rockland and State of New York, have invented a certain new, original and ornamental design for an Illuminable Wall Plaque or Similar Article, of which the following is a specification, reference being had to the accompanying drawings forming a part thereof and in which:

Figure 1 is a front elevational view of an illuminable wall plaque or similar article embodying my new design;

Figure 2 is a top plan view thereof;

Figure 3 is a bottom plan view thereof; and

Figure 4 is an elevational view of one side of my new design. Since both sides of the design are identical, only one side is illustrated.

I claim:

The ornamental design for an illuminable wall plaque or similar article, substantially as shown.
OTTO A. KUHLER.
